CLOSURE AND DISPENSER FOR CONTAINERS

Jorge Teofilo Freeman, Buenos Aires, Argentina

Application April 29, 1940, Serial No. 332,275
In Argentina December 26, 1939

3 Claims. (Cl. 221—66)

This invention relates to a dispensing and closure forming device for use in connection with cardboard or similar containers of granular or powdered material from which it is only desired to remove a portion of the contents at any one time.

Certain products such as various breakfast cereals, coffee, sugar and the like, for instance, are largely put out in cardboard boxes, which must be broken open to get at the contents. Once this is done, the product soon loses its crispness, aroma or freshness generally, as the case may be, and frequently becomes unpalatable, or requires artificial drying before it is again fit for use.

It is therefore one of the objects of my invention to provide a combination dispensing and closure forming device particularly adapted for mounting in a cardboard container, by means of which any desired portion of the contents may be dispensed without breaking open the container, and which enables the dispensing outlet to be closed and substantially sealed against the penetration of dampness when the dispensing operation is completed.

Another object of the invention is to provide a device for the purpose which will enable the contents to be dispensed in the form of a relatively small restricted stream and which while so functioning will agitate the contents and prevent possible clogging of the same at the outlet, so that a smaller outlet can be used than is otherwise practicable.

In this respect therefore the device is suitable for use in permanent glass jars and other containers adapted for refilling and from which it is desired to dispense the contents in small quantities, and which may be mounted in a normal inverted position against a wall or like surface.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a perspective view of a container equipped with my improved dispenser.

Figure 2 is a side view of the device as mounted in the container and in a closed position.

Figure 3 is a face or front view of the device

as mounted in the container and in a dispensing position.

Figure 4 is a side view of the device as in a dispensing position.

5 Figure 5 is a perspective view of the device detached.

Referring now more particularly to the characters of reference on the drawing, the device comprises what may be termed a paddle wheel, 10 formed of suitable thin rigid material and consisting of a body having a central hub portion 1 and a plurality of arms 2 projecting therefrom in evenly spaced relation thereabout. Vanes 3, preferably of triangular form, extend along and 15 project in a common transverse direction from one side edge of the arms at right angles thereto, the vanes being so set that their widest part, or their base, is adjacent the hub as clearly shown, while their apex is adjacent the outer end of the 20 arms.

The wheel is set flatly against one side wall 4 of a container near a corner thereof and so that the arms just clear the adjacent top (or bottom) wall 5 of said container. The wheel is 25 turnably mounted in place by means of an axial spindle 6 rigid therewith and projecting through wall 4, where it is connected with a turning knob 7 of suitable form.

A small outlet opening 8 is formed in the wall 30 5 in radial alignment with the wheel and one of the arms is formed at its outer end with an arcuate shutter 9 projecting from the same face of the wheel as the vanes, and adapted to substantially contact with the under surface of the 35 wall 5 and to cover the opening 8 when the wheel is in a certain position. In order that this position may be readily indicated to the operator, an indicating arrow 10 or other mark is placed on the knob 7.

40 In operation, when it is desired to dispense from the container, the same is inverted with the outlet over the vessel into which it is desired that the contents shall fall, and the knob is twirled. This of course intermittently opens the outlet to

45 allow the contents to issue therefrom, while at the same time the rotating vanes, being positioned so that they cut across the path of movement of the contents within the container, keep the same agitated besides tending to force such contents from the outlet. When a dispensing operation is completed, the knob is turned until the indicating mark 10 denotes that the outlet is closed.

55 It may here be noted that the number and size of the arms and vanes, and the size of the outlet

opening, will vary according to the type and size of the product to be dispensed, as obviously many different products may be dispensed with my device.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A dispensing agitator for a container comprising a rotatable unit formed from a sheet of initially flat bendable material, said unit including a hub portion, flat arms radiating from the hub portion in the plane of said hub and in circumferentially spaced relation, vane portions formed on side edges of said arms and at right

angles to the flat thereof; an axial pin fixed on and projecting from the hub in a direction opposite said vanes, and an operating member on the free end of said pin.

5 2. A device as in claim 1 in which said vanes are triangular in configuration; the edges of the vanes nearest the axis of rotation being parallel thereto.

3. A dispensing agitator for a container comprising a rotatable unit formed from a sheet of initially flat bendable material, said unit including a hub portion, flat arms radiating from the hub portion in the plane of said hub and in circumferentially spaced relation, 10 vane portions formed on side edges of said arms and at right angles to the flat thereof, and an arcuate shutter on the outer end of one arm beyond but projecting in the same direction as said vanes, the shutter curving on an axis parallel to the axis of rotation of the hub; an axial pin fixed on and projecting from the hub in a direction opposite said vanes, and an operating member on the free end of said pin.

JORGE TEOFILO FREEMAN.
